UNITED STATES PATENT OFFICE.

DEAN C. DOUGLAS, OF LOS ANGELES, CALIFORNIA.

RAILWAY-CROSSING.

1,238,005.

Specification of Letters Patent. Patented Aug. 21, 1917.

Application filed September 5, 1916. Serial No. 118,459.

To all whom it may concern:

Be it known that I, DEAN C. DOUGLAS, a citizen of the United States, residing at Los Angeles, in the county of Los Angeles and State of California, have invented new and useful Improvements in Railway-Crossings, of which the following is a specification.

This invention relates to a railway crossing for use at steam or street railway intersections.

It is an object of this invention to provide a crossing that is continuous avoiding gaps and obviating the jarring, pounding, strain and noise such as exists in the ordinary crossing.

It is another object to provide a crossing of the type described which is automatic in its action, mechanically actuated and avoids the use of motors, springs or the like.

It is a further object to provide a crossing in which movable rail sections are arranged to provide continuous rails for crossing trains or cars, and which is so constructed as to minimize the liability of the moving sections becoming jammed.

I accomplish these objects by means of the embodiments of my invention illustrated in the accompanying drawings, in which:

30 Figure 1 is a plan view of a crossing showing the preferred form.

Fig. 2 is an elevation of the construction shown in Fig. 1.

Fig. 3 is an enlarged fragmentary view 35 as seen on the line 3—3 of Fig. 1.

Fig. 4 is a fragmentary plan view showing the detail of connections between rail sections.

Fig. 5 is a section as seen on the line 40 5—5 of Fig. 4.

Fig. 6 is an elevation of sections of the rail showing a modified form of my invention.

Fig. 7 is a fragmentary detail in elevation 45 illustrating a safety device applied to the rail and wedge.

Fig. 8 is an enlarged detail plan view showing the connections between the running rails and movable rail sections.

50 Referring to the preferred form of construction, and particularly to Fig. 1, A and A' indicate pairs of running rails intersected by running rails B and B'. The intersections are preferably in the form of castings of which there are four, one at

each corner of the square formed by the intersections. Bridging the castings and completing the intersections are bridging rails 9, 10, 11 and 12. A suitable base plate 13 is provided upon which the crossing is 60 mounted. Secured to the base plate are brackets C, 14, 15 and 16. Bridging rails 9, 10, 11 and 12 are of similar construction and the mechanism for operating is the same for each rail. A description of one will 65 suffice.

Bridging rail 11 comprises sections 17 and 18 pivotally secured to each other and to bracket 15. I prefer to use the pivotal connection shown in Figs. 4 and 5 which comprises slotting rail 17 at the end and placing a tongue 19 upon section 18. The slot in section 17 conforms to the shape of a tongue 19 which is curved at the end. Registering apertures are formed in sections 70 17 and 18 and a pivot bolt 20 is mounted thereon. Pivot bolt 20 is secured to bracket 15. This construction permits sections 17 and 18 to swing about the pivot bolt. Grooves 21 and 22 are formed in the running rail intersections and tongues 23 and 24 on the rail sections register with grooves 75 21 and 22 respectively. This construction prevents transverse movement of the rail sections, and forms a secure connection. 80

By referring to Fig. 2 it will be noted that when sections 17 and 18 are moved upwardly with the upper surface thereof level with running rail B, a continuous rail is formed for the passage of the car wheel. 90 When sections 17 and 18 are lowered the continuity of the rail is broken and a space is permitted for the flange of the car wheels to pass on the rails A and A'. The lowered position is shown in Fig. 3. The crossing 95 is so constructed that as the car moves upon the same along running rails B and B' bridging rails 9 and 11 are raised to form continuous surfaces with the running rails last referred to, while bridging rails 10 and 12 are lowered to permit the flanges to pass thereover. The reverse action occurs when a car crosses on the running rails A and A'. 100

An automatic mechanically actuated mechanism is provided for moving the rails. On 105 the lower surface of each of the bridging rail sections are slots which coöperate with wedges. Referring to Figs. 2 and 3 section 17 is provided with a slot 25 and section 18 is provided with a similar slot 26. A slid- 110

able wedge 27 coöperates with slot 25 and a similar wedge 28 coöperates with slot 26. When the wedges are moved from the slot toward the free end of the bridging rail sections the sections are raised. When the wedges are disposed beneath the slots the rail sections are lowered, thus in Fig. 3, wedge 28 is shown disposed in slot 26, while in Fig. 2 wedge 28 is moved out of the slot 10 and supports the rail section 18 in its upper position. Wedge 27 is pivotally connected to a link 29, the other end thereof being connected to a link 30. Wedge 28 is pivotally connected to a link 31, the other end thereof being connected to link 30. On the free end of link 30 is a pin 32 which is disposed in a slot formed in the end of a lever 33. Lever 33 is pivoted to the base plate as indicated at 34 and is swung by means of a trip 35 20 which is disposed on the flange side of the running rail A.

When lever 33 is swung in one direction to move link 30 links 29 and 31 will be moved to pull wedges 27 and 28 below the recesses 25 25 and 26 and the rail sections 17 and 18 will drop as indicated in Fig. 3 to provide for a free and continuous passage of car wheels along running rails A and A' and bridging rails 10 and 12. Link 30 is connected to one 30 arm 36 of a member 38 which is pivotally mounted upon the base plate 13. Other arms are provided to which are connected links similar to link 30, each of the links controlling a pair of wedges under a bridging rail so that when one link is moved the other links are also moved.

When link 30 is moved to lower rail sections 17 and 18, link 39 is moved to dispose the wedges under bridging rail 9 in such a 40 position that the sections thereof are also lowered. Link 40 is moved to dispose the wedges under bridging rail 10 so that the latter is raised, and similarly link 41 moves the wedges under bridging rail 12 to lift the latter. A trip is provided on one of a pair 45 of running rails at each approach to the crossing. All of these trips are of similar construction and the description of one will suffice. Trip 42 is shown in Fig. 3 and comprises a lever 43 pivoted on rail B at one end. Pivotally connected to the free end is a link 44 which is pivotally secured to a crank 45, the latter being pivotally mounted upon the rail. Crank 45 engages lever 46 which corresponds to lever 33. The flange of a car 50 wheel operates the trip, it engages by depressing it, also lowering the corresponding trip at the opposite rail and raising the other pair of trips. Assuming that a car is approaching the crossing on the running rails B and B', the flange thereof will engage a lever 43 and force it downwardly, moving crank 45 and lever 46 so that the slot at the end thereof moves toward bridging rail 10. 55 Link 40 is moved to the left, and member 38

turned through the arc of a circle. The wedges under bridging rail 10 are moved to position beneath the slots and the rail is lowered. Movement of member 38 moves link 41, bridging rail 12 is lowered and the adjacent trip lowered. Link 30 is so moved that wedges 27 and 28 are forced outwardly toward the ends of rail sections 17 and 18, bridging rail 11 and trip 35 are raised. Movement of link 39 causes a similar raising 70 of the sections of bridging rail 9 and the trip corresponding to trip 35. A continuous surface is thus afforded for the car wheels to travel along running rails B and B' over the crossing, the bridging rails 10 and 12 80 having been lowered so that the flange does not ride upon them. The rails will remain in this condition until a car approaches the crossing along the running rails A and A'. The flange on a car wheel will then engage 85 trip 35 and member 38 will be moved by lever 33 and link 30. This causes a lowering of bridging rails 9 and 11, and a raising of bridging rails 10 and 12 with a consequent raising of trip 42 and the corresponding trip 90 adjacent rail 12.

In Fig. 6 I have shown a modified form of bridging rails in which two brackets 47 and 48 are mounted upon the base plate. A rail section 49 is disposed between brackets 47 95 and 48 and is immovable. Pivotally secured to one end of rail section 49 is a section 50, and pivotally secured to the other end of rail section 49 is a section 51. Wedges 52 and 53 coöperate with rail sections 50 and 51 in a manner similar to that described in the operation of the preferred form.

In Fig. 7 I have shown a safety device which will insure dropping of the rail sections. The forms of construction before described in the dropping of the rail depends upon its own weight, and if the crossings are kept clean there will be little liability of the rails failing to lower. Rail section 17' is provided with a slot 25' and a wedge 27' 105 coöperating therewith in the same manner as the construction shown in Fig. 2. Mounted upon the base plate is a bracket 54, and pivotally mounted thereon is a bell crank 55. The vertical arm of the bell crank is disposed to be engaged by wedge 27' as it is moved below the slot 25'. The horizontal arm is disposed above a lug 56 on rail section 17'. As wedge 27' is moved to register with slot 25' it will engage the vertical arm of bell 110 crank 55 and move the latter so that the horizontal arm will engage lug 56 and force the rail downwardly. If the rail drops by its own weight the bell crank 55 will move with it and the wedge 27' will not engage 115 the bell crank. Each rail section would be equipped with one of the safety devices shown in Fig. 7.

What I claim is:

1. In a railway crossing, the combina- 130

- tion of bridging rails comprising sections pivotally mounted so as to swing the ends to and from the level of the running rails and having recesses formed on the under-
5 side, a base, members movable on said base into and out of said recess to swing a pair of bridging rails to the level of the running rail and the other pair below the running rails, and means to operate said members.
- 10 2. In a railway crossing, the combination of bridging rails comprising sections mounted so as to move the ends thereof to and from the level of the running rails, mechanism to move a pair of bridging rails to the level of the running rails and the other pair below said running rails, movable wedges disposed below the ends of said sections, and linkage secured to said wedges to move the latter and raise the section of one pair of bridging rails and lower the section of the other pair.
- 15 3. In a railway crossing, the combination of bridging rails comprised of sections mounted so as to move the ends thereof to and from the level of the running rails, mechanism to move a pair of bridging rails to the level of the running rails and the other pair below said running rails, movable wedges disposed below the ends of said sections, linkage secured to said wedges to move the latter, and raise the sections of one pair of bridging rails and lower the sections of the other pair, and a trip for operating said linkage disposed to be actuated by the flange of a car wheel.
- 20 4. In a railway crossing, the combination of bridging rails comprised of sections pivotally mounted so as to swing the ends thereof to and from the level of the running rails, mechanism to swing a pair of bridging rails to the level of the running rails, and the other pair below said running rails, movable wedges disposed below the free ends of said sections to raise and lower the same, linkage interconnecting said wedges to simultaneously move the latter, those under the sections of one pair of bridging rails lowering the latter and those under the sections of another pair raising the latter, and trips for operating said linkage one disposed adjacent the running rail end of a pair of bridging rails, and one adjacent the running rail end of the other pair of bridging rails and disposed to be actuated by the flange of a car wheel.
- 25 5. In a railway crossing, the combination of bridging rails comprised of sections pivotally mounted so as to swing the ends thereof to and from the level of the running rails, mechanism to swing a pair of bridging rails to the level of the running rails, and the other pair below said running rails, movable wedges disposed below the free ends of said sections to raise and lower the same, linkage interconnecting said wedges to simultaneously move the latter, those under the sections of one pair of bridging rails lowering the latter and those under the sections of another pair raising the latter, and trips for operating said linkage one disposed adjacent the running rail end of a pair of bridging rails, and one adjacent the running rail end of the other pair of bridging rails and disposed to be actuated by the flange of a car wheel.
- 30 6. In a railway crossing, the combination of bridging rails comprised of sections pivotally mounted so as to swing the ends thereof to and from the level of the running rails, mechanism to swing a pair of bridging rails to the level of the running rails, and the other pair below said running rails, movable wedges disposed below the free ends of said sections to raise and lower the same, linkage interconnecting said wedges to simultaneously move the latter, those under the sections of one pair of bridging rails lowering the latter and those under the sections of another pair raising the latter, and trips for operating said linkage one disposed adjacent the running rail end of a pair of rails and one adjacent the running rail end of the other pair of bridging rails, said trips mounted to be actuated by the downward pressure of the flange of a car wheel.

In witness that I claim the foregoing I have hereunto subscribed my name this 22nd day of August, 1916.

DEAN C. DOUGLAS.
